UNITED STATES PATENT OFFICE.

FOREST CHENEY, OF CHICAGO, ILLINOIS, ASSIGNOR TO CHENEY TALKING MACHINE COMPANY, OF CHICAGO, ILLINOIS, A CORPORATION OF ILLINOIS.

SOUND-REPRODUCING MACHINE.

1,395,092.

Specification of Letters Patent. Patented Oct. 25, 1921.

Application filed August 11, 1917. Serial No. 185,659.

To all whom it may concern:

Be it known that I, FOREST CHENEY, a citizen of the United States, and resident of Chicago, in the county of Cook and State of Illinois, have invented certain new and useful Improvements in Sound-Reproducing Machines, of which the following is a specification.

This invention relates to sound reproducing machines, and more particularly to sound amplifier means therefor.

As is well known to those skilled in the art, while the initial vibrations of the diaphragm of such machines potentially set up all of the complex air vibrations necessary to produce the fundamental tones and overtones going to make up the character and tone color of all the instruments or voices (the tones of which are being reproduced), said air vibrations are nevertheless very weak and must be amplified and strengthened in order that the sounds will be reproduced in sufficient volume.

One of the objects, therefore, of my invention is to increase, in a novel manner, the volume of sound reproducing machines.

Another object is to provide a simple and effective combination of parts to increase the volume of sounds adapted to meet the various requirements for successful commercial operation.

These and other objects are accomplished by providing in a sound reproducing machine a sound chamber having an inlet and an outlet, the latter of which is smaller than the inlet.

The invention is illustrated on the accompanying sheet of drawings in which,

Figure 1 is a fragmentary plan view of a sound reproducing machine embodying my invention;

Fig. 2 is a fragmentary rear elevation of the same machine, and

Fig. 3 is a detail sectional view taken in the plane of line 3—3 of Fig. 2.

The various novel features of the invention will be apparent from the following description and drawings, and will be particularly pointed out in the appended claims.

In order to reproduce sound which is pleasing to the ear and which may be carried a relatively great distance, for example, in a concert hall, it is necessary that the volume of the sound reproducing machine be sufficiently great. The quality of the sound or

tone is dependent upon volume. When I speak of volume, I mean fullness of tone as distinguished from loudness.

I have illustrated my invention in connection with a sound reproducing machine 10 having means for rotating a record 11 operatively associated with which is a sound box 12 to which is connected a sound or tone arm 13, the latter of which is preferably constructed in accordance with the arrangement disclosed in my Patent No. 1,170,802, granted February 8, 1916. The final section 14 of the tone arm 13 is preferably curved to an angle of 90 degrees forming an elbow, and the lower end thereof has a flange or enlargement 15 which rests upon the top 16 of a cabinet. The final section 14 of the tone arm communicates with the inlet opening of a sound member or distributor 17, the size of the inlet opening being indicated by the area 75 inclosed by the four walls of the distributor 17, shown in Fig. 3.

I have found by experiment that the volume of sound-reproducing machines may be greatly increased for developing fuller and richer tones of improved quality by providing the throat of the machine, which in this instance I call the distributor 17, with a plurality of sound outlets, the size of each of which is less than the size of the inlet of 85 the distributor. To this end I have provided a distributor 17 with a plurality of oppositely arranged sound outlets 18 which register with tone amplifying conduits or members 19, the final sections 20 of which are 90 in the form of elbows which register with orchestral sections 21 preferably constructed in accordance with my Patent No. 1,170,800, granted February 8, 1916. These orchestral sections register with resonators 22, which in 95 this instance are supported on the top 16.

By means of this arrangement wherein the distributing chamber is provided with a plurality of sound outlets, the size of each of which is smaller than the sound inlet of the 100 distributing chamber, it is possible to greatly increase the volume, quality, fullness and richness of a tone. In this particular instance I have provided the sound distributor 17 with two sound outlets. However, it is to 105 be understood that this number may be decreased to one or increased if so desired without departure from the scope of my invention.

There may be various modifications of my 110

invention as herein particularly shown and described, and it is my intention to cover all such modifications which do not depart from the spirit and scope of the invention as set forth in the following claims.

I claim:

1. In a talking machine, the combination with a sound producing device, of a tone arm, a sound distributing chamber having 10 an inlet opening and a plurality of outlet openings each of less cross-section than the inlet opening, a sound conduit leading from the tone arm to the inlet of said distributing chamber, and a plurality of sound amplifiers, one communicating with each of said outlet openings.
2. In a talking machine, the combination with a sound producing device, of a tone arm, a cubical sound distributing chamber 20 having an inlet opening and a plurality of outlet openings each of less cross-section than the inlet opening, a sound conduit leading from the tone arm to the inlet of said distributing chamber, and a plurality of sound amplifiers, one communicating with each of said outlet openings.
3. In a talking machine, the combination with a sound producing device, of a tone

arm, a sound distributing chamber having an inlet opening and a plurality of outlet 30 openings each of less cross-section than the inlet opening, a sound conduit leading from the tone arm to the inlet of said distributing chamber, a plurality of sound conduits, one leading from each of said outlet openings, 35 and a plurality of sound amplifiers, one communicating with each of said plurality of sound conduits.

4. In a talking machine, the combination with a sound producing device, of a tone 40 arm, a sound distributing chamber having an inlet opening and a plurality of outlet openings of a combined cross-sectional area less than the cross-sectional area of said inlet opening, a sound conduit leading from 45 the tone arm to the inlet of said distributing chamber, and a plurality of sound amplifiers, one communicating with each of said outlet openings.

Signed at Chicago, Illinois, this 30th day 50 of July, 1917.

FOREST CHENEY.
